Primary Examiner — Mojtaba Tehrani(74) *Attorney, Agent, or Firm* — Miller Nash LLP**CLAIM**

The ornamental design for an aiming reticle, as shown and described.

DESCRIPTION

FIG. 1 is a front elevational view of an aiming reticle; FIG. 2 is an enlarged detail view of a central portion of the aiming reticle of FIG. 1;

FIG. 3 is a detail view of the aiming reticle portion of FIG. 2 illustrating an illuminated center dot;

FIG. 4 is a detail view of the aiming reticle portion of FIG. 2 illustrating an illuminated dot on a vertical element of the aiming reticle;

FIG. 5 is a detail view of the aiming reticle portion of FIG. 2 illustrating multiple illuminated dots on a vertical element of the aiming reticle; and,

FIG. 6 is a detail view of the aiming reticle portion of FIG. 2 illustrating an illuminated dot on a horizontal element of the aiming reticle and illustrating an illuminated dot on a vertical element of the aiming reticle.

The evenly broken lines in FIG. 1 depict unclaimed portions of the aiming reticle. The alternating long and short dash broken lines depict unclaimed boundary of the isolated view shown in FIG. 2. The broken lines form no part of the claimed design.
